UNITED STATES PATENT OFFICE.

THOMAS HOOKER, OF SYRACUSE, NEW YORK.

MECHANICAL SPEED-INDICATOR.

No. 821,804.

Specification of Letters Patent.

Presented May 29, 1906.

Application filed September 12, 1903. Serial No. 172,903.

To all whom it may concern:

Be it known that I, THOMAS HOOKER, of Syracuse, in the county of Onondaga, in the State of New York, have invented new and useful Improvements in Mechanical Speed-Indicators, of which the following, taken in connection with the accompanying drawings, is a full, clear, and exact description.

This invention relates to improvements in mechanical speed-indicators in which the comparative speed of a revolving element is first indicated with reference to a predetermined or normal speed requirement and the actual speed is then ascertained through the medium of a manually-adjusted differential-speed mechanism coacting with the revolving element and a suitable registering device, as a cyclometer.

The primary object of this invention is to enable the operator to ascertain the comparative or actual speed of any revolving part or parts and to automatically register such speed without reference to any time-indicating device, such as a watch or clock, so that the indicated speed as registered may be referred to after the device has been removed from the part being tested.

Other objects will appear in the following description.

In the drawings, Figure 1 is a top plan of my improved speed-indicator, a part of the top wall being broken away for disclosing the underlying mechanism. Figs. 2, 3, and 4 are sectional views taken, respectively, on lines 2 2, Fig. 1, and 3 3 and 4 4, Fig. 2. Figs. 5 and 6 are sectional views taken, respectively, on lines 5 5 and 6 6, Fig. 1. Fig. 7 is a detail view of a speed multiplying and reducing attachment for the main driving-spindle.

Similar reference characters indicate corresponding parts in all the views.

In carrying out the objects stated a revolute driving shaft or spindle 1 is journaled at its outer end in a bearing 2 in one of the side walls of an inclosing case or supporting frame 3, and its inner end is seated in a bearing 4 in the side of an upright standard 5, which rises from the base or bottom of the case. This spindle is held from endwise movement by any well-known means, and its outer end is provided with a clutch section or collar 6, into which is inserted one end of a spur 7, the latter being applied to the revolving part the speed of which is to be ascertained.

A friction wheel or disk 8 is feathered on

the spindle 1 to rotate therewith and is frictionally engaged with a similar but larger friction disk or wheel 9 for transmitting rotary motion to the latter. The axes of the disks 8 and 9 are disposed at substantially right angles to each other, and in this instance the periphery of the disk 8 is in frictional contact with the lower face of the disk 9 at one side of its axis. The disk 9 is mounted on a spindle 10, having its lower end stepped in a bearing in the upper end of the standard 5, and its upper end extends above the disk 9 and is seated in an axially-movable bearing, as a sliding rod 11. This sliding rod or bearing 11 is guided in an opening 12 in the upper wall of the case 3 and is actuated endwise in one direction, as outwardly, by one or more centrifugally-operated levers or arms 13, which are mounted upon and rotate with the disk 9 and upon which the lower end of the sliding rod 11 rests.

The levers 13 are fulcrumed on the disk 9 at opposite sides of its axis and are suitably weighted, so as to move automatically toward and from the axis of revolution as the disk is revolved, the amount of throw depending upon the speed of revolution. This centrifugal motion of the weighted ends of the levers causes the elevation or outward thrust of the plunger-rod 11 against the action of a spring-arm 14, which bears against the outer end of said rod and operates to return the latter and also the weighted levers to their starting positions when the centrifugal force is less than the counteracting force of the spring, the tension of the spring being regulated by any suitable means, as an adjusting-screw 15. This motion which is imparted to the spring 14 by the centrifugal members is utilized to actuate an indicator-finger 16 along a suitable dial 17, and this is accomplished through the medium of a rock-lever 18 and a rack and pinion 20 and 21, so that when the disk 9 is revolved at a predetermined or normal speed the finger 16 will register with the zero graduation of the dial. The finger 16 and dial 17 are of course exposed to view and are here shown as located upon and above the top of the case 3, the finger 16 having one end secured to a vertical rock-shaft or spindle 22, which is journaled in the top wall of the case and carries the pinion 21, and its other end is movable along the dial 17, which is secured directly to the top of the case concentric with the spindle 22. The rack 20 meshes with and actuates the

pinion 21 and is formed on one end of a lever, which is fulcrumed at 23, while the opposite end of said lever is engaged by one arm of the lever 18, the other end bearing on the free end of the spring 14.

It is now apparent that when the spur 7 is applied to a rotating element similar rotary motion will be imparted to the disk 9 through the medium of the spindle 1 and disk 8 and that the weighted ends of the levers 13 will be thrown or moved radially a distance proportionate to the speed of revolution of the disk 9, which centrifugal throw operates the index-finger 16 along the dial 17 through the medium of the plunger 11, spring 14, lever 18, and rack and pinion 20 and 21. The weighted levers 13 and spring 14 are adjusted so that when the disk 8 is in its innermost position and revolved at a certain speed—in this instance two hundred revolutions per minute—it will cause the disk 9 to also revolve at a certain speed, known as the "constant" or "normal" speed, which in turn will cause the finger 16 to move to a certain position or point relatively to the dial. This point is marked naught, ("0;") and when the finger 16 is brought into registration with this point it indicates that the disk 9 is running at a constant or normal speed, while the speed of the disk 8, which is the speed of the part being tested, is of course variable. In order to maintain this constant or normal speed of the disk 9, the disk 8 is movable axially at the will of the operator by means of a screw 24 and nut 25, the screw being journaled in the sides of the case, and is provided with a handpiece 26, while the nut 25 is mounted on a screw and engaged with a groove in the hub 19 of the disk 8, so that by rotating the screw the nut and disk are moved axially toward and from the axis of the disk 9 to change the point of contact between the two disks. It will now be seen that when the disk 8 is moved to its extreme outer position or point of contact with the disk 9 it will require a certain speed greater than the two hundred revolutions per minute previously mentioned of the disk 8 to bring the disk 9 to its normal speed and to thereby cause the finger 16 to move to the zero-point on the dial. The ratio of distances of the disk 8 in its extreme inner and outer positions from the axis of the disk 9 is in this instance one to five, and therefore if it requires two hundred revolutions per minute of the disk 8 when in its innermost position to bring the finger 16 to the zero-point it will require one thousand revolutions per minute of said disk when in its extreme outer position to produce the same result, and these two speeds represent the maximum capacity of the device without the use of a multiplying and reducing attachment, presently described.

The rotation of the screw 24 in moving the disk 8 axially to maintain a constant or nor-

mal speed for the disk 9 is utilized to actuate the cyclometer 29 through the medium of suitable intermeshing gears 27 and 28, which, together with the mechanism of the cyclometer, are adjusted so that when the disk 9 is brought to its normal speed the actual speed of the disk 8 and part being tested is indicated in figures by the cyclometer. For example, if it requires a speed of two hundred revolutions per minute of the disk 8 to bring the disk 9 to its normal speed the cyclometer is caused to register "200," or if the speed of the disk 8 is five hundred revolutions per minute the rotation of the screw 24 to shift the disk 8 axially so as to again bring the disk 9 to its normal speed would cause the cyclometer to register "500." In like manner any speed of a revolving part within the capacity of the device is indicated in figures by the cyclometer through the medium of the screw 24 and its connections with the parts of the cyclometer.

In some instances the speed of the part being tested may be above or below the capacity of the device just described, and I therefore provide a multiplying and reducing attachment 30, Fig. 7, which in this instance consists of a sectional spindle 31, the spindle-sections having a common axis, but are rotatable at different speeds, and either may be applied to the coupling-section of the spindle 1 while the other receives the spur 7. The sections of the spindle 31 are provided with gears 32 and 33 of different sizes, which mesh, respectively, with gears 34 and 35 on a second spindle 36, these gears 34 and 35 being also of unequal size, and the smaller gears of each spindle mesh with the larger gears of the other spindle. The gears 32, 33, 34, and 35 are of such pitch as to increase or diminish the speed of the spindle 1 above or below the speed of the revolving part by a definite factor—in this instance 5—so that when the section 33 is applied to the revolving part the speed of which is to be tested and the other section is applied to the spindle 1 the latter is rotated five times as fast as said revolving part, while, on the other hand, when the disposition of the sections 32 and 33 is reversed the speed of the spindle 1 is reduced to one-fifth of the speed of said revolving part. It will now be seen that the ratio between the highest and lowest speeds of the disk 8 without the multiplying and reducing attachment is the same as the ratio between the two speeds of said attachment and that in ascertaining the actual speed of any revolving element it is first necessary to adjust the screw 24 and disk 8 so as to bring the disk 9 to its normal speed, which normal speed is ascertained in the manner hereinbefore described.

In the operation of my invention the device is taken in hand by the operator and the spur 7 applied to the revolving part the speed of which is to be determined. This

causes the spindle 1 and disk 8 to revolve at the same speed as the revolving part, and therefore transmits rotary motion to the disk 9, which in turn operates the finger 16 along the dial 17. Now suppose the disk 9 is revolved at a speed above its normal speed, which in this instance would indicate that the speed of the part being tested was above two hundred revolutions per minute, this would cause the finger 16 to pass beyond the zero-point on the dial, and in order to cause the cyclometer 29 to register the actual speed of the part being tested it will be necessary to adjust the screw 24 to bring the disk 8 to such a position as would reduce the speed of the disk 9 until the finger 16 was registered with the zero graduation on the dial. This rotation of the screw would actuate the cyclometer and produce a reading in figures which would indicate the actual speed of the revolving element. In like manner any speed between two hundred and one thousand revolutions per minute is indicated in figures by the cyclometer without the use of the multiplying and reducing attachment. Now assuming that the speed of the revolving part to be tested is greater than the capacity of the apparatus—say, for instance, two thousand revolutions per minute, without the use of the multiplying and reducing attachment—then the section of the spindle 31 having the gear 32 is connected to the spindle 1, and the spur 7 is connected to the section of the spindle 31 having the gear 32. If the spur 7 is now applied to the revolving part running two thousand revolutions per minute, it is evident that the spindle 1 will be rotated one-fifth of two thousand revolutions per minute, or four hundred revolutions per minute, as the ratio of the speeds of the two sections of the spindle 31, in this instance as five to one. The screw 24 is now rotated to adjust the disk 8 so as to cause the disk 9 to revolve at its normal speed, as indicated by the finger 16 registering with the zero-mark on the dial. This rotation of the screw would cause the cyclometer to read "400"—that is, the speed of the spindle 1—and as this speed is one-fifth of the actual speed of the revolving part being tested said actual speed may be obtained by multiplying the reading of the cyclometer by five. On the other hand, assuming that the speed of the revolving part being tested is less than the capacity of the apparatus without the use of the multiplying and reducing attachment—as, for example, forty revolutions per minute—then the section of the spindle 31 having the gear 32 is connected to the spindle 1 and the spur 7 is coupled to the section of the spindle 31 having the gear 33. Now if this spur is applied to the revolving part with a speed of forty revolutions per minute the spindle 1 will be rotated five times as fast as the spur 7, or two hundred revolutions per

minute, and the screw 24 is then rotated to adjust the disk 8 until the disk 9 is brought to its normal speed, indicated by the finger 16 registering with the zero-mark on the dial, and this rotation of the screw will cause the cyclometer to read "200," or the speed of the spindle 1, and as this speed is five times as great as the actual speed of the part being tested such actual speed may be obtained by dividing the reading of the cyclometer, as "200," by five, which will give forty revolutions per minute, or the actual speed of the part being tested.

Having described my invention, what I claim, and desire to secure by Letters Patent, is—

1. A mechanical speed-indicator comprising a revolving element having an independent centrifugal movement produced by its rotation, means actuated by the centrifugal movement of said element to indicate its speed of rotation, variable-speed driving means to rotate said element, and manually-operated means for adjusting said driving means to cause said element to revolve at a constant speed.

2. A speed-indicator comprising a revolving element having an independent centrifugal movement, variable-speed driving means to rotate said element, manually-operated means for adjusting said driving means to cause said element to revolve at a constant speed, and a movable index-finger operatively connected to said element and actuated by its centrifugal movement.

3. A speed-indicator comprising a revolving disk and variable-speed driving means therefor adjustable to keep said disk at a constant speed, a centrifugally-actuated element on the disk, and a movable indicating member operatively connected to and actuated by said element.

4. A speed-indicator comprising a revolving disk and variable-speed driving means therefor adjustable to keep said disk at a constant speed, a centrifugally-actuated element on the disk, a plunger actuated by said element and an indicating-finger operatively connected to and actuated by said plunger.

5. A speed-indicator comprising a revolving disk and variable-speed driving means therefor and adjustable to keep said disk at a constant speed, a centrifugally-actuated element on the disk, a plunger actuated by said element and means actuated by the plunger to indicate the speed of rotation of the disk.

6. A mechanical speed-indicator comprising a revolving element having an independent centrifugal movement produced by its rotation, a plunger actuated by the centrifugal movement of said element, variable-speed driving means movable axially to keep the revolving element at a constant speed, manually-operated means for adjusting said driving means axially, and means actuated by

the plunger to indicate the speed of such rotation.

7. A speed-indicator comprising a revolvable element having an independent centrifugal movement, a spring connected to act against such movement, means for adjusting the tension of the spring, variable-speed driving means to rotate said element and to cause it to rotate at a constant speed, and an index-finger operatively connected to and actuated by said element to indicate said constant speed.

8. A speed-indicator comprising a revolving disk and variable-speed driving means therefor adjustable to bring the disk to a constant speed, a centrifugally-operated element on the disk and actuated by its rotation, a movable indicating member operatively connected to and actuated by the centrifugally-operated element to indicate said constant speed and means to return said element to its normal position.

9. In a speed-indicator the combination of a rotary disk, a variable-speed driving-disk frictionally engaged with the former disk and adjustable axially to bring the former disk to a constant speed, a centrifugally-operated element carried by the former disk and actuated by its rotation, a plunger actuated by said element, and an index-finger operatively connected to and actuated by the plunger to indicate said constant speed.

10. In a speed-indicator the combination of a rotary disk, a variable-speed driving-disk frictionally engaged with the former disk and adjustable axially to bring the former disk to a constant speed, a centrifugally-operated element carried by the former disk and actuated by its rotation, a plunger actuated by said element, and an index-finger operatively connected to and actuated by the plunger to indicate said constant speed, and a spring for retracting the plunger.

11. A speed-indicator comprising a revolving element having an independent centrifugal movement, variable-speed driving mechanism for rotating said element, said mechanism being adjustable to bring the revolving element to a constant speed, manually-operated means for adjusting said driving mechanism and a movable indicating member operatively connected to and actuated by said revolving element to indicate such constant speed.

12. A speed-indicator comprising a driving member operable under variable speeds and a driven member actuated thereby, and manually-operated means for adjusting the driving member to cause the driven member to rotate at uniform normal speed.

13. A speed-indicator comprising a revolving element having an independent centrifugal movement, variable-speed driving mechanism for rotating said element, manually-operated means connected to change the po-

sition of the driving means to vary the speed of said element, an index-finger connected to and actuated by said element, and an index-operatively connected to and actuated by the manually-operated means.

14. A speed-indicator comprising two rotary disks in frictional contact, one driving the other, the driving-disk being movable endwise to change the position of contact and to vary the speed of the driven disk, a centrifugally-operated element on the driven disk and an indicating member operatively connected to and actuated thereby, a screw connected to shift the driving-disk, and a cyclometer connected to and actuated by the screw.

15. A speed-indicator comprising a revolving disk and operating means therefor, a centrifugally-actuated element on the disk, and a movable indicating member operatively connected to and actuated by said element, a manually-operated screw connected to shift the position of the disk, operating means to change the speed of rotation of the disk and a cyclometer actuated by the screw, for the purpose set forth.

16. In a speed-indicator, a variable-speed driving member and a rotary driven member, one member being adjustable at the will of the operator relatively to the other to keep the driven member at a constant speed and manually-operated means for adjusting said adjustable member.

17. In a speed-indicator, a variable-speed driving member, and a rotary driven member, one member being adjustable relatively to the other at the will of the operator to keep the driven member at a constant speed, manually-operated means to adjust said adjustable member, and means to indicate when the driven member is revolved at a constant speed.

18. In a speed-indicator, a variable-speed driving member and a rotary driven member, one member being adjustable relatively to the other at the will of the operator to keep the driven member at a constant speed, means to adjust the adjustable member and a speed-registering device actuated by said means.

19. In a speed-indicator, a variable-speed driving member and a rotary driven member, one member being adjustable relatively to the other at the will of the operator to keep the driven member at a constant speed, manually-operated means to adjust said adjustable member, and means actuated by the driven member to indicate when it is revolving at a constant speed.

20. In a speed-indicator, a variable-speed driving member and a rotary driven member, one member being adjustable relatively to the other to keep the driven member at a constant speed, and means actuated by the driven member to indicate when it is revolv-

ing at a constant speed, additional means to adjust the adjustable member, and a speed-indicating device actuated by the additional means.

- 5 21. In a speed-indicator, a variable-speed driving member and a rotary driven member, one member being adjustable relatively to the other at the will of the operator to keep the driven member at a constant speed and 10 manually-operated means for adjusting said adjustable member in combination with a multiplying attachment operatively connected to the driving member and adapted to be applied to the part, the speed of which is to 15 be tested.
22. In a speed-indicator, a variable-speed driving member and a rotary driven mem-

ber, one member being adjustable relatively to the other at the will of the operator to keep the driven member at a constant speed and 20 manually-operated means for adjusting said adjustable member, a speed-multiplying device operatively connected to the driving member and adapted to be applied to the part, the speed of which is to be tested and 25 means brought into action by the adjustment of the manually-adjustable member to indicate such speed.

In witness whereof I have hereunto set my hand on this 8th day of September, 1903.

THOMAS HOOKER.
